[57] CLAIM

The ornamental design for cloth covered shape, as shown and described.

DESCRIPTION

FIG. 1 is a front elevational view of a cloth covered shape; FIG. 2 is a back elevational view of the cloth covered shape of FIG. 1;

FIG. 3 is a right side elevational view of the cloth covered shape of FIG. 1;

FIG. 4 is a left side elevational view of the cloth covered shape of FIG. 1;

FIG. 5 is a top plan view of the cloth covered shape of FIG. 1;

FIG. 6 is a bottom plan view of the cloth covered shape of FIG. 1;

FIG. 7 is a front elevational view of a cloth covered shape; FIG. 8 is a back elevational view of the cloth covered shape of FIG. 7;

FIG. 9 is a right side elevational view of the cloth covered shape of FIG. 7;

FIG. 10 is a left side elevational view of the cloth covered shape of FIG. 7;

FIG. 11 is a top plan view of the cloth covered shape of FIG. 7;

FIG. 12 is a bottom plan view of the cloth covered shape of FIG. 7;

FIG. 13 is a front elevational view of a cloth covered shape; FIG. 14 is a back elevational view of the cloth covered shape of FIG. 13;

FIG. 15 is a right side elevational view of the cloth covered shape of FIG. 13;

FIG. 16 is a left side elevational view of the cloth covered shape of FIG. 13;

FIG. 17 is a top plan view of the cloth covered shape of FIG. 13;

FIG. 18 is a bottom plan view of the cloth covered shape of FIG. 13;

FIG. 19 is a front elevational view of a cloth covered shape; FIG. 20 is a back elevational view of the cloth covered shape of FIG. 19;

FIG. 21 is a right side elevational view of the cloth covered shape of FIG. 19;

FIG. 22 is a left side elevational view of the cloth covered shape of FIG. 19;

FIG. 23 is a top plan view of the cloth covered shape of FIG. 19; and,

FIG. 24 is a bottom plan view of the cloth covered shape of FIG. 19.

The cloth covered shapes of the present invention are intended for decorative use on clothing, window dressings, and other fabric items. For example, a plastic shape may be surrounded by cloth and the cloth secured by a rubber band to form the cloth covered shape.

The broken line(s) which define the bounds of the claimed design form no part thereof.
